CLAIM

The ornamental design for a phone case, as shown and described.

DESCRIPTION

FIG. 1 is an illustration of a front view of a phone case showing our new design;

FIG. 2 is an illustration of a back view of the phone case; FIG. 3 is an illustration of a left side view of the phone case; FIG. 4 is an illustration of a right side view of the phone case;

FIG. 5 is an illustration of a top view of the phone case; FIG. 6 is an illustration of a bottom view of the phone case; FIG. 7 is an illustration of an isometric view of the back of the phone case; and,

FIG. 8 is an illustration of an isometric view of the front of the phone case.

The broken lines immediately adjacent the shaded surfaces represent the bounds of the claimed design. All other broken lines depict environmental subject matter that forms no part of the claimed design. The broken lines and unshaded regions bounded by broken lines form no part of the claimed design.
